UNITED STATES PATENT OFFICE

113,770

DESIGN FOR A COMBINED BURNER AND GRATE

Alvin G. Sherman, Grosse Pointe, Mich., assignor to Sherman-Jackson-Roose Company, Detroit, Mich., a corporation of Michigan

Application May 16, 1938, Serial No. 77,219

Term of patent 14 years

To all whom it may concern:

Be it known that I, Alvin G. Sherman, a citizen of the United States of America and residing at Grosse Pointe, in the county of Wayne and State of Michigan, have invented a new, original, and ornamental Design for a Combined Burner and Grate, of which the following is a specification, reference being made to the accompanying drawing, forming part thereof.

Fig. 1 is a perspective view of the combined burner and grate embodying my new design.

Fig. 2 is a plan view thereof.

I claim:

The ornamental design for a combined burner and grate, substantially as shown.

ALVIN G. SHERMAN.
